UNITED STATES PATENT OFFICE

2,557,122

COAXIAL CRYSTAL DETECTOR AND LINE TERMINATION DEVICE

J. Plumer Leiphart, United States Navy

Application September 27, 1945, Serial No. 618,999

1 Claim. (Cl. 250—31)

(Granted under the act of March 3, 1883, as amended April 30, 1928; 370 O. G. 757)

1

This invention relates broadly to coaxial lines as used for the transmission of radio-frequency energy and, more particularly, to a coaxial device for simultaneously terminating such a coaxial line in a desired impedance and rectifying the radio-frequency output thereof.

In the practice of those electrical arts that contemplate the transmission of radio-frequency energy along a coaxial line, there frequently arises occasion to provide a special termination for such a coaxial line. This is commonly true, for example, when it is desired to connect external metering or measuring apparatus thereto for the purpose of measuring the voltage, current, or power output of a radio-frequency transmission system. As is well known, however, unless the termination thus effected is such as to present to the coaxial line an impedance substantially equal to the characteristic impedance of the line, the observed measurements will be distorted by effects arising from impedance mismatch, reflection, and standing waves along the coaxial line. It is known also that when alternating currents are caused to circulate through a network of connecting leads at very high frequencies, particularly frequencies in excess of 100 megacycles per second, the effects of lead inductances and stray wiring capacitances can assume such serious proportions as to necessitate special provision for neutralizing them. For these reasons, therefore, such common methods of connecting radio-frequency metering apparatus to a coaxial transmission line as by means of wire leads have been found to introduce serious errors at frequencies approaching the ultra-high-frequency range, unless steps are taken to compensate therefor by the insertion of some adjustable impedance-matching device, as is known in the art. However, the use of such prior impedance-matching devices generally has the disadvantage that their tuning tends to vary considerably with the operating frequency; so that to provide a "fixed-tuned" coaxial type terminating device, capable of operation over a wide range of ultra-high frequencies, would be of advantage in the art.

It is accordingly an object of this invention to provide a simple and compact coaxial terminating device by means of which any coaxial transmission line, of given cross-sectional dimensions and characteristic impedance and carrying radio-frequency energy at frequencies ranging from very low to beyond the ultra-high-frequency band, may be terminated in substantially its characteristic impedance at any terminal point along such line at which the device may be inserted.

2

Since radio-frequency apparatus frequently for its activation requires that the input thereto be of a rectified or direct-current (D. C.) character, it is accordingly another object of this invention to provide coaxial terminal rectifying means operative to produce, for whatever utilization purpose and with reasonable accuracy over an unusually wide range of operating frequencies, substantially half-wave rectification of the radio-frequency voltage or current output from any coaxial line of given cross-sectional dimensions and characteristic impedance at any terminal point thereof at which said rectifying means is utilized.

15 An important feature of this invention is that it provides a compact, coaxially-arranged terminal connecting and rectifying device by means of which radio-frequency measuring apparatus, requiring for its operation half-wave rectified voltages or currents, may be operatively connected to any terminal point along a coaxial transmission line of given cross-sectional dimensions and characteristic impedance; and by means of which also any inaccuracies arising 20 from impedance mismatch, reflection, and standing waves, or from lead inductances and stray wiring capacitances, may be minimized or eliminated entirely, over an unusually wide range of 25 operating frequencies, when measuring radio-frequency voltages, currents, or power at said 30 terminal point.

In accordance with this invention, the device comprises a parallel network, coaxially mounted and arranged adaptably to engage a coaxial 35 transmission line terminal connector, and consisting of a resistance in parallel with a capacitor and with a unidirectional rectifying crystal, the capacitor and crystal being connected in series.

40 In one preferred embodiment of the invention, the resistance comprises a non-inductive disk-shaped resistor having a central hole therethrough, contiguous with which and contiguous also with the outer periphery of one side of the disk are provided concentric annular terminal 45 means adaptable to engage the inner and outer conductors of a coaxial receptacle, respectively. The resistor, capacitor, and crystal each are arranged to be separately replaceable, and to provide for this contingency a separable coaxial mounting in which they are enclosed. Said mounting comprises essentially: a coaxial connector; a coaxial housing so constructed and arranged as to accommodate the aforesaid parallel network and complete the requisite electrical connections thereof, and to provide a coaxial receptacle for said coaxial connector such that

the outer and inner conductors thereof may be electrically connected across the aforesaid disk resistor; supporting structure for said coaxial mounting; means for making external electrical connections thereto across the said capacitor; and means for attaching said coaxial connector at one end to said coaxial receptacle and at the other end to a coaxial transmission line terminal connector so as to connect the said coaxial line electrically across the aforesaid parallel network.

The foregoing, together with other objects, advantages, and features of the invention, may be understood more fully from the following description of one preferred embodiment thereof when taken in conjunction with the accompanying drawings, wherein a crystal voltmeter arrangement utilizing the invention is illustrated by way of example only, and in which:

Fig. 1 is a front elevational view of a preferred embodiment of the invention, with rectifying crystal cartridge removed to show the arrangement of certain of the contact fingers;

Fig. 2 is a longitudinal section of the device illustrated in Fig. 1, taken substantially along the line 2—2 of Fig. 1, but with the crystal cartridge shown housed therein in its proper operating position;

Fig. 3 is a front elevational view, on considerably enlarged scale, showing a typical "circular dag" disk resistor such as employed in the Fig. 1 device;

Fig. 4 is a fragmentary sectional view of the Fig. 3 resistor, still further enlarged, taken substantially along the line 4—4 of Fig. 3 and showing details of the structure thereof;

Fig. 5 is a schematic diagram of the electrical circuit and associated components of a crystal voltmeter arrangement utilizing the device shown in Figs. 1 and 2; and

Fig. 6 is a side elevational view of the rectifying crystal cartridge.

Referring now to the drawings, there is illustrated therein one practical embodiment of the invention, designed for use in conjunction with a suitably sensitive meter to measure radio-frequency voltages of relatively small magnitude (such as the output voltages from an ultra-high-frequency signal generator) along a standard 50-ohm coaxial transmission line.

As illustrated in Figs. 1 and 2, reference numeral 10 generally designates the hollow coaxial housing wherein there is mounted an insertible unidirectional rectifier means: specifically, the stepped cartridge-type crystal 11 (see Fig. 6), of which one example known to the art is the so-called Western Electric "type 1N21" crystal. The housing 10 is shown as comprising a flat annular metal disk-like front part 12 and a separable coaxial rear part 13; the latter being formed by the hollow metallic cylindrical member 14 and the coaxial connector member 15, coupled together by the metallic coupling ring 16. A flat circular flange 17 is provided at one end of the member 14. Disposed between the front disk 12 and the flange 17 of the separable rear part 13 is an annular wafer-like member 18 of mica or other suitable dielectric material, which together with the disk 12 and the flange 17 forms a capacitor, the purpose of which will become more apparent from the subsequent description of the device. Metal screws 19 secure the members 12, 17 and 18 together, each of these screws being electrically insulated from the front disk 12 by means of an insulating sleeve 20 of

vulcanized hard rubber or other suitable insulating material, and being screw-threaded at their inner ends into the flange 17 to provide good electrical connection therewith. The two lower screws 19 shown also serve to mount the rear part 13 of the housing 10 securely on (and connect it electrically to) the metal supporting bracket 21, which in turn is fixedly mounted on and electrically connected to the metal base 23 by the screws 22.

The substantially half-wave rectified D. C. output of the device may be removed by means of leads, as shown at 24 and 25, the lead 24 being connected to the front disk 12 by means of a short screw which is sufficiently short to penetrate only into disk 12. Output lead 25 forms the ground return lead and is connected, in this illustrative example, to the base 23 by means of a screw 22' attached thereto at some convenient point, such as shown in Fig. 2, the electrical circuit being completed to the rear part 13 of the device by way of base 23, bracket 21, and the two lower screws 19.

It may be remarked that the use of a supporting bracket 21 and base 23 is entirely optional and for convenience of mounting only. Both could be eliminated without affecting in any way the intended operation of the device, in which event the ground lead 25 would be connected to the rear part 13 of the mounting directly or by attaching it to one of the screws 19.

The wafer-like capacitive dielectric layer 18 shown is, in practice, approximately .005 inch thick and presents a capacitance of approximately 100 micromicrofarads. This wafer is provided with suitable marginal perforations and with a central opening, for passage of the screws 19 and insertion of the crystal cartridge 11, respectively.

Both the front part 12 and the member 14 of the rear part 13 of the mounting 10 are axially perforated and recessed to permit the insertion of crystal cartridge 11 and provide coaxial cylindrical chambers 26 and 27 respectively, of appropriate size and cross-sectional dimensions. Annularly arranged metal fingers 28, which protrude outwardly and forwardly from the periphery of the central aperture in the front part 12 of the device, embrace and firmly grip the cylindrical flanged metal cap 29 of the crystal cartridge 11, thereby establishing good electrical conductive contact therewith. Similarly, the internal axially-located and annularly-arranged metal fingers 30 perform a similar function with reference to the cylindrical metal tip 31 of the crystal cartridge 11. Fingers 30 project from and are integral with the metal plug 30', which forms the inner coaxial conductor of member 14. The other end of the plug 30' is of reduced diameter and screw-threaded for attachment to the correspondingly hollowed and threaded central conductor 32 of the coaxial connector 15. When plug 30' is screwed home through the central hole 33 of the disk-shaped, non-inductive resistor 34 (which in this illustration is of the type known to the art as "circular dag"), a firm contact is established between the central annular metallic terminal 35 of resistor 34 (considerably enlarged views of which are shown in Figs. 3 and 4) and the central conductor 32, regardless of the direction which resistor 34 "faces"—i. e., either towards the crystal cartridge 11 or towards the coaxial connector member 15. The connector member 15 is provided at one end with a circular flange 36 which is engaged by the coupling nut 16, whereby a firm contact is estab-

lished with the end of the member 14. The member 14 is externally threaded as indicated at 37 to receive said coupling nut 16, whereby the clamping and electrical connection of the circumferential annular metallic terminal 38 of resistor 34 between the flange 36 and the end of the member 14 is effected when the metallic coupling nut 16 is screwed down tightly in place.

The "input" end of the central conductor 32 of coaxial connector 15 is shown in this particular illustration as being of a split-sleeve construction, having spaced fingers 40, while the outer conductor of connector 15 is externally threaded at its "input" end as indicated at 41. This arrangement is designed to accommodate the common type of coaxial transmission line terminal connector (not shown), which includes a central axial metal prong and an external loosely-rotatable threaded sleeve (similar in operation to coupling nut 16) for seating connections firmly. Other types of coaxial line terminal connectors may be accommodated in similar fashion, as by alternatively constructing the coaxial connector member 15 to include such a central axial prong and/or such an external threaded sleeve at its input end as may be necessary to "mate" the particular terminal connector being used with the coaxial transmission line—in fact, in practice a set of various types of interchangeable connectors 15 might profitably be constructed, to cover the various possibilities. Also, while connector member 15 is illustrated in Fig. 2 as being filled with solid polystyrene 45, this is purely for purposes of insulation and support and is not vital to the action of the device. Any suitable dielectric material can be used for the filling 45, or it can be eliminated entirely.

Figs. 3 and 4 illustrate the construction of the "circular dag" resistor 34, in which Fig. 3 is a front elevational view thereof at approximately 6 times normal size, while Fig. 4 shows a further enlarged and considerably exaggerated fragmentary cross-section thereof taken along the line 4—4 of Fig. 3. In this illustrative example, the annular central terminal 35 and circumferential annular terminal 38 each comprise "flash" coatings of silver, approximately .010 inch thick, impressed on one face of a circular backing disk 42 of Bakelite or other suitable insulating material. The non-inductive intermediate annular resistive section 43 shown in Figs. 3 and 4 comprises a "flash" coating of carbon, approximately .001 inch thick, impressed on the same face of base 42 throughout the area intervening between annular terminals 35 and 38, and sufficient to present an electrical resistance of the order of sixty ohms between said terminals. The resistor 34 also has a central hole 33 of sufficient diameter to just permit passage of the threaded portion of plug 30', as illustrated in Fig. 2.

The equivalent circuit for the preferred model herein discussed is shown schematically in Fig. 5, with connections to the coaxial transmission line terminal T and output meter M indicated by dotted lines, and operates as follows to provide a substantially half-wave rectified D. C. output across terminals 26 and 22'. Radio-frequency impulses from coaxial transmission line T impressed at the input end of connector 15, as at points 40 and 41, effectively "see" the parallel network comprising the non-inductive circular dag resistor 34 across the series-parallel combination of unidirectional rectifying crystal 11 in series with radio-frequency by-pass capacitor 18 and meter M in parallel. For an impressed impulse

of one polarity (which for purposes of discussion we shall call "positive") the D. C. resistance R_x offered by crystal 11 is quite low (of the order of 200 to 300 ohms in a practical case of the "Type 1N21 crystal" cited), whereas for impressed impulses of the opposite (or "negative") polarity its D. C. resistance R'_x is very high (probably of the order of several thousand ohms). Thus the magnitudes of the currents and resultant voltage drops across the various elements of the parallel network will differ widely, according as they arise from impulses of positive or negative polarity impressed at input points 40 and 41. They also will vary with frequency, but to a much less extent. In this illustration, the "positive" direction of current flow through the crystal 11 is assumed to be from tip 31 to cap 29, as is commonly the case in practice.

It may help to clarify the discussion if we assign definite values, of an order of magnitude we might expect to meet in a practical application, to certain of the variables involved. Accordingly, let us assume, in addition to the already-mentioned 50-ohm characteristic impedance of the coaxial transmission line, that the actual frequency f is 1000 megacycles per second, that the resistances offered by crystal 11 at that frequency are $R_x=250$ ohms in the "positive" direction and $R'_x=2500$ ohms in the "negative" direction, that the magnitudes of resistance 34 and capacitance 18 are $R=62.5$ ohms and $C=100$ micromicrofarads, respectively, and that the resistance R_m of meter M, "looking in" from terminals 26 and 22', is 100 ohms. Then the magnitude of the reactance $|X_c|$ offered by capacitor 18 at frequency f will be, employing the usual formula, quite small:

$$|X_c| = \frac{1}{2\pi f C} = \frac{1}{2\pi (1000 \times 10^6) (100 \times 10^{-12})} = 1.59 \text{ ohms}$$

Hence it is evident that the by-pass capacitor 18 will indeed effectively shunt out meter M as far as any "negative" radio-frequency impulses that might slip through crystal 11 are concerned, the magnitude of the combined impedance of meter M and capacitor 18 working out in the example cited to be approximately

$$\frac{(1.59) \times (100)}{(1.59) + (100)} = 1.57 \text{ ohms}$$

at frequency f . Furthermore, since the magnitude R of resistance 34 is only 62.5 ohms, whereas the combined impedance of the other branches of the parallel network will be approximately 2500 ohms in the negative direction, it is clear that more than 97% of all "negative" radio-frequency impulses impressed at input points 40 and 41 in this illustrative example will be by-passed through resistor 34. Also, the combined impedance of the parallel network in the negative direction will have a magnitude of approximately 61 ohms.

On the other hand, positive impulses impressed at the input points 40 and 41 will effectively "see" the 50-ohm characteristic impedance of the coaxial line, since the magnitude of the combined impedance $|Z|$ of the parallel network will then be approximately:

$$|Z| = \frac{(62.5)(250 + 1.57)}{62.5 + 250 + 1.57} = 50 \text{ ohms}$$

Thus, the impedance of the coaxial line will be perfectly matched for all positive impulses, and nearly so for all negative impulses, thereby virtually eliminating the undesirable effects of im-

pedance mismatch, reflection, or standing waves that so frequently arise when terminal connections are made to a coaxial transmission line.

Furthermore, it is evident that the current flowing through crystal 11 in the positive direction will be substantial, being about one-fifth of the total such current furnished by the coaxial line. Hence, in spite of the shunting effect of capacitor 18, adequate half-wave rectified D. C. current will reach meter M to actuate a sensitive movement. For example, if the magnitude of the radio frequency voltage across input points 40 and 41 in the foregoing illustration is assumed to be two volts, a current of the order of 40 milliamperes will flow across the 50-ohm parallel network in the positive direction, of which approximately one-fifth, or 8 milliamperes, will pass through crystal 11. Approximately $1/100$ of the 8 milliamperes, or 80 microamperes of half-wave rectified D. C. current, will then flow through meter M, which is more than required by, say, a 50-microampere movement. Also, since the current in leads 24 and 25 will be essentially D. C. in character, the effects of lead inductance and stray capacitance introduced by such leads will be negligible.

The device as illustrated and discussed herein is suitable for connection to any terminal T along any 50-ohm coaxial transmission line of given cross-sectional dimensions. It is to be noted, however, that the invention and the principles involved are not limited in their practical application to 50-ohm coaxial lines of given dimensions, nor to voltage measurements. For example, by properly choosing the depth of the "flash" carbon coating 43, resistances 34 can be constructed of sufficient range of magnitude R to make it possible to present, in combination with the other elements of the parallel network, a combined input impedance of any magnitude likely to be desired in practice. Coaxial transmission lines of different cross-sectional dimensions would simply require that correspondingly different dimensions be adopted in the construction of the coaxial elements of the device. It is also evident that meter M can be calibrated in terms of the known impedance of the parallel network to read voltages, currents, or power. Furthermore, terminals 26 and 22' can be left open if for any reason it is desired merely to terminate the coaxial line (either in approximately its own characteristic impedance or in a different impedance) without using the rectified output; or any other device requiring for its operation substantially half-wave rectified D. C. currents or voltages may be connected to said terminals.

The effective frequency range of the device is determined chiefly by the reactance $|X_C|$ of capacitor 18, since its magnitude varies markedly with frequency, and to a lesser extent by probable coincident variations in the magnitude of the resistance R_x of crystal 11 in the positive direction. Considerably larger magnitudes C of by-pass capacitance 18 will be required in order properly to shunt meter M at low radio frequencies; while marked variations in the magnitude of R_x will require offsetting changes in the magnitude R of resistance 34. By so choosing the values as to strike an average for a particular band of frequencies, measurements of consider-

able accuracy can be obtained over that band, the accuracy improving as the width of the operating band of frequencies is cut down. A rough working model, constructed approximately as described herein, was found to give voltage readings accurate to within 10% over the wide frequency range of 10 kilocycles to 1000 megacycles per second.

The effective voltage or current range of the device depends at the low end largely on the sensitivity of the meter M used therewith, and at the high end on the "burn-out" point of the crystal 11. The above-mentioned working model was found to read down to .01 volt and up to at least 2 volts.

It remains merely to point out that the device is not limited to the use of type 1N21 crystals—any type of unidirectional rectifying crystal 11 having a suitably high "back-to-front resistance ratio" and mounted in a metal-ended cartridge may be employed, provided that the coaxial crystal housing 10, including fingers 28 and 30, is constructed to fit it.

It will be obvious to those skilled in the art that further changes or modifications may be made in the preferred embodiment of the invention herein described without departing from the spirit thereof, and it is to be distinctly understood, therefore, that no limitations are intended other than are imposed by the scope of the appended claim as limited by the prior art.

The invention described herein may be manufactured and used by or for the Government of the United States of America for governmental purposes without the payment of any royalties thereon or therefor.

What is claimed is:

An output termination for a coaxial line of the internal conductor and sheath type comprising a coaxial coupler for receiving the end of the line and having internal and external conductors terminating in the same plane, a flat annular resistor abutting in said plane against the conductors to terminate the coaxial line and coupler with the desired impedance, a central cavity member in electric contact with the outer portion of the resistor and opposite the external coupler conductor, a crystal rectifier unit in the cavity, wholly outside the coaxial coupler, and spaced from the resistor, a conductor member connecting the crystal unit to the center of the resistor and the internal coupler conductor, and a conductive cap member contacting the crystal unit and capacitatively coupled to the cavity member, the cap and cavity members constituting output electrodes for the line.
